UNITED STATES PATENT OFFICE.

PETER D. GRAAFF, OF FRESNO, CALIFORNIA.

PORTABLE WARDROBE.

SPECIFICATION forming part of Letters Patent No. 708,341, dated September 2, 1902.

Application filed April 27, 1901. Serial No. 57,749. (No model.)

To all whom it may concern:

Be it known that I, PETER D. GRAAFF, a citizen of the United States, residing at Fresno, in the county of Fresno and State of California, have invented new and useful Improvements in Portable Wardrobes, of which the following is a specification.

My invention relates to portable wardrobes; and it consists in the novel construction and arrangement of parts hereinafter set forth and described.

The object of my invention is to obtain a portable wardrobe which is applicable to a flat wall and which is simple in construction. I accomplish this by the means of the wardrobe illustrated in the drawings, in which—

Figure 1 is a view in perspective of the invention. Fig. 2 is a front elevation of the wardrobe, a portion of the top being in vertical section to show the construction. Fig. 3 is a bottom plan view.

In the annexed drawings, 1 represents the top of the wardrobe, having suitable sides 2, back 3, and front 4. On the under side of the top 1 is secured a pair of depending brackets 5, which are provided with openings to receive a detachable rod 6, which is provided with a head at one end and screw-threads at its other end adapted to receive a nut 7, thereby preventing its accidental displacement. Upon the rod 6 are appended suitable hooks 8, the same being adapted to receive clothing. Clothing-hooks are also secured to the lower portion of the back of the wardrobe, as at 9.

The numeral 10 designates the longitudinal curtain-rod, which extends on the under side front portion of the top, some distance below the surface thereof, and is held in position by a support 13, which not only serves the purpose of securing the rod, but also prevents the sagging of the same. The ends of the rod are curved and bent at right angles to the rod, so as to form branch straight arms 10^a, having their terminal ends secured to the back 3 of the structure. Mounted upon the

rod 10 and its arms 10^a are rings 12, to which is attached a curtain 11, adapted to have a sliding movement on the rod 10, and also by means of the curvature of the arms 10^a the curtain can be slidably arranged on said arms, whereby to fold the curtain at the ends of the wardrobe, thereby exposing the entire front of the same, so that any desired article of clothing can be hung on the hook or readily removed therefrom.

In securing my wardrobe in place I prefer to use eyebolts 14; but I do not wish to be understood as confining myself to this particular securing means, as their mechanical equivalent may be used in lieu thereof.

Having thus fully described my invention, what I claim as new, and desire to secure by Letters Patent, is—

A portable wardrobe comprising a top, sides and back, brackets extending centrally downward from the under side of the top having a detachable rack suspended thereby, hooks secured to the lower front edge portion of the back, a rod extending longitudinally on the under front surface portion of the top having a support centrally arranged to hold and prevent sagging of the same, the opposite ends of the rod being curved and bent to form therewith transverse straight right-angular branch arms having their terminal ends secured to said back, rings slidably mounted on the rod and its arms, a sectional curtain connected to said rings of the rod and arms whereby said curtain is movable on the rod and also from the rod to the straight arms, or vice versa, by means of said curvature at the intersection of said rod and said arms, substantially as specified.

In testimony whereof I affix my signature in presence of two witnesses.

PETER D. GRAAFF.
